CHIN KWONG SOON, OF SEATTLE, WASHINGTON.

KNITTED GARMENT.

1,160,542.

Specification of Letters Patent. Patented Nov. 16, 1915.

Application filed August 21, 1913. Serial No. 785,863.

To all whom it may concern:

Be it known that I, CHIN KWONG SOON, citizen of the Republic of China, residing at Seattle, in the county of King and State of Washington, have invented a certain new and useful Improvement in Knitted Garments, of which the following is a specification.

My invention relates to improvements in knitted garments commonly known as "sweaters" and particularly to that class of sweaters that are adapted to be buttoned in front like a coat or waistcoat, and the object of my improvement is to provide a sweater, made of knitted yarn, whose body portion shall be a single integral structure the bottom edge of which, by a novel disposition of stitches, is adapted to be strong to withstand a strain that would tend to stretch it, whereby such edge may better preserve the shape of the body portion of the garment, and whereby such bottom edge shall be finished to be smooth and neat in appearance without sewing or binding with other pieces of yarn. I accomplish this object by devices illustrated in the accompanying drawings, wherein—

Figure 1 is a fragmentary view in elevation of the inner side of the lower portion 30 of a sweater embodying my invention; Fig. 2 is a like view of the outer side of the same; Fig. 3 is a like view of the edge of the same, and Fig. 4 is a fragmentary view in elevation showing the inner side of the lower portion of a sweater containing a modified form of my invention.

Like reference numerals indicate like parts throughout the drawing.

Heretofore sweaters, whose body portion 40 is knitted by forming ribs, have had their bottom edges finished by sewing thereto a binding of tape, or such edges have been formed by the cessation of knitting, and where no binding has been sewn to such edge then the garment quickly loses its desired shape by reason of the frequent stretching that is incidental to its use and the edge soon breaks and wears out.

Referring to Fig. 1 of the drawings, which 50 shows the inner surface of the lower portion of a knitted sweater opened outwardly, 6, 6, are opposite sides of the front of the garment, while 7 is the back of the garment with a portion of it broken away and removed for convenience of illustration, 8, 8 are button holes disposed in a reinforcing

strip 9 that is sewn on the inner surface of the front vertical edge of one side of the garment while buttons 10 indicated by dotted lines are sewn to the corresponding vertical edge of the opposite front of the garment. 60

The body of the garment is formed of a closely-knitted ribbed fabric presenting vertical ribs 11 while the lower edge of each of the front portions 6, 6 is formed by extending two ribs 12 and 13 of each front portion 6, that are disposed adjacent to the vertical ribs of the back portion 7, lengthwise of the bottom edge to, and upwardly on, each of 70 the outer vertical edges of said front portions 6, 6 and such two ribs 12 and 13 are joined to the bottom of the vertical ribs 11 to become an integral portion of the whole structure. 75

Of course, if desirable, more than two ribs may be diverted from a point near the back portion 7 to be joined as described to the bottom ends of the vertical ribs and to extend thence upwardly upon the outer vertical 80 edge of the front portions 6, 6.

At a point on each side of the back portion 7 of the garment and at the lower edge thereof a recess is formed by extending downwardly the back portion 7 from the 85 points of departure of the ribs 12 and 13 in a curved direction toward the outer vertical edges of the front portions 6, 6, such recess serving to better adapt the garment to conform to the shape of a person to make 90 it more comfortable to such person.

In Fig. 2 is shown the outer surface of the structure of Fig. 1 and in Fig. 3 is shown a view of a portion of the bottom surface of the lower edge of one of the front 95 sides 6, 6.

Fig. 4 illustrates a slightly modified form of my invention, by a view of the inner side of the lower portion of a sweater, which modification consists in merging two vertical 100 ribs 14 and 15, that are disposed adjacent to ribs each side of the back portion 16, into a single rib that is disposed to extend along the bottom edge of each side, respectively, and joined to be integral with the bottom 105 ends of the vertical ribs 17 whereby such single rib serves to resist strains that tend to stretch the bottom edges of the garment and whereby such bottom edge may be much more durable and preserve the shape of the 110 garment. At the point of departure of the ribs 12, 13 or the ribs 14, 15 from the back

portion 7, ribs 7' extend transversely of the back portion whereby to reinforce the back portion and prevent ripping at the point of juncture of the aforesaid ribs with the back portion.

Obviously, the form of the lower portions of sweaters or other like knitted garments may be modified to suit one's fancy without departing from the spirit of my invention, the essential feature of which consists in disposing one or more vertical ribs to extend horizontally from points near the back portion of a garment to unite with the bottom ends of the vertical ribs forming the front portion of such garment whereby such horizontally ribbed bottom edges of the front portion of such garment may be adapted to resist a strain that would tend to stretch the garment out of shape.

20 What I claim is:

A garment comprising a back section and two side sections, the latter connected at their inner longitudinal edges to the outer longitudinal edges of the back section, each

of said sections being composed of a knitted fabric made up of vertically extending ribs, and each of said side sections having its innermost vertical rib curved outward away from the back section near its point of connection with the latter and extended under the lower ends of the other vertical ribs of said side sections at substantially right angles thereto to reinforce said side sections transversely and provide a selvage edge therefor which constitute an integral part 35 of said side sections, the lower end of said back section being provided with transverse ribs extending between the diverging points of the innermost vertical ribs of the side sections whereby to prevent ripping at this 40 point.

In witness whereof, I, hereunto subscribe my name this twenty ninth day of July A. D., 1913.

CHIN KWONG SOON.
